UNITED STATES PATENT OFFICE.

JEHAL H. SIMONDS, OF NEW YORK, N. Y.

IMPROVEMENT IN HEATERS.

Specification forming part of Letters Patent No. 35,043, dated April 22, 1862.

To all whom it may concern:

Be it known that I, JEHIAL H. SIMONDS, of the city, county, and State of New York, have invented a new and Improved Air-Heating Furnace; and I do hereby declare that the following is a full, clear, and exact description of the same, reference being had to the accompanying drawings, making a part of this specification, in which—

Figure 1 is a side sectional view of my invention, taken in the line *x x*, Fig. 2; Fig. 2, a horizontal section of the same, taken in the line *y y*.

Similar letters of reference indicate corresponding parts in the two figures.

This invention relates to an improved air-heating furnace of that class in which air-heating tubes are placed in a hot-air chamber inclosed within walls of masonry or metal to form a chamber to receive the cold air to be heated.

To enable those skilled in the art to fully understand and construct my invention, I will proceed to describe it.

A represents the fire-pot of the furnace, *B* the ash-box, and *C* the feeding-passage of the fire-pot.

D is a hot-air chamber, which may be of quadrilateral form, supported at its front end by the fire-pot and ash-box and at the back end by an upright framing, *E*, as shown in Fig. 1. The sides and back of the hot-air chamber *D* are made of convex form, so as to present a series of alternate convex and concave surfaces, as shown clearly in Fig. 2, and designated by *a b*. This curvature of the sides and back of the hot-air chamber gives a much greater radiating-surface than could be obtained by straight sides and a straight back forming plane surfaces.

Within the hot-air chamber *D* there are placed a series of vertical tubes, *F*, which pass entirely through *D* and communicate at their upper and lower ends with the external air; there being no communication between said tubes and *D*. The tubes *F* are not permanently secured in or attached to *D*, but are fitted therein as follows: Each tube *F* is provided at its upper end with a flange, *c*, which extends entirely around it and projects downward, so as to fit in an annular recess, *d*, in

the top plate, *e*, of the hot-air chamber *D*. The recesses *d* encompass the openings *f* in the top plate, *e*, in which the tubes *F* are fitted, and the recesses *d* are filled with sand, *g*, which forms a seal and makes an air-tight joint. (See Fig. 1.) The lower ends of the tubes *F* are fitted on vertical tubular projections *h*, which are on the inner surface of the bottom plate, *i*, of the hot-air chamber *D*, and are encompassed by annular recesses *j*, which are also filled with sand, *k*, to receive the lower ends of the tubes *F*, as shown in Fig. 1. By this arrangement the tubes *F* may, when rendered defective by use, be readily detached and withdrawn from the hot-air chamber *D* and new ones inserted in their places.

The sides and back of the hot-air chamber *D*, as well as the top and bottom plates thereof, are of cast-iron, the recesses *d* of the top plate, *e*, being cast in it, and the tubular projections *h* and recesses *j* are also cast with the bottom plate, *i*.

G is a pendent curved plate attached to the top plate, *e*, of the hot-air chamber *D* and extending the whole width of the latter. This plate serves as a deflector, and it extends downward a distance equal to half the height of the hot-air chamber *D*, as shown in Fig. 1. The deflector *G* is directly in front of a series of vertical draft-duction tubes, *H*, which are arranged in the form of a circle, and are attached at their lower ends to a cap, *I*, provided at its edge with a flange, *k'*, which is fitted in an annular groove, *l*, in the top plate, *e*, said groove being filled with sand, *m*, to form a tight joint. The upper ends of the tubes *H* communicate with a dome-shaped chamber, *J*, which communicates at its center with the upper end of a vertical pipe, *K*, which communicates with the smoke-pipe *L*. The lower part of the pipe *K* is of conical form, as shown at *n*, and this conical part *n* passes through the center of the cap *I* and projects down a trifle into *D*. The conical part *n* of the pipe admits of the lower end of the same having a small orifice, *o*, the use of which will presently be explained.

The hot-air chamber *D* is inclosed within an apartment or cold-air chamber, *L'*, the walls of which may be of masonry, and are represented in red, Fig. 2. This cold-air cham-

ber has openings in the lower parts of its walls to admit of the admission of cold air, and hot-air-conveying pipes communicate with the upper part of the chamber L'.

The operation is as follows: When a fire is kindled in the fire-pot A, the products of combustion pass along through the hot-air chamber D and all around and between the tubes F, fitted therein. The deflector G gives a circuitous route to the products of combustion in D, as indicated by the black arrows, and causes the tubes F to be subjected their entire length to a more uniform degree of heat than they otherwise would be, as without the deflector G the products of combustion would pass directly into the tubes H, as indicated by the red arrows; but the deflector G causes the products of combustion to descend from the upper part of D and underneath it (the deflector) before passing into the tubes H. The products of combustion enter the dome-shaped chamber J and pass down the pipe K into the smoke-pipe L. The orifice o at the lower end of pipe K is sufficiently large to admit of soot falling or discharging itself from said pipe into D, and at the same time not large enough to admit of a draft-passage into or through it. This arrangement, therefore, obviates the necessity of a damper, which has hitherto been employed and operated manually in order to allow of the escape of soot from the draft-pipe. The employment of the damper involves the necessity of care and forethought, and neglect and carelessness fre-

quently cause the draft-pipe to become choked with soot, so as to render the furnace very inefficient. This contingency is avoided by my invention, as the pipe-cleansing feature is entirely self-operating. The cold air passes through the tubes F, as indicated by the blue arrows, and is heated thereby, the heated air being conveyed by pipes, as usual, to the apartments designed to receive it.

Having thus described my invention, what I claim as new, and desire to secure by Letters Patent, is—

1. Securing the tubes F in the hot-air chamber D by means of the flanges c on the upper ends of the tubes, fitted in sand in recesses d in the top plate, e, of the hot-air chamber, and by having the lower ends of the tubes fitted over vertical tubular projections h on the bottom plate, i, of the hot-air chamber and within sand in recesses j, which surround the tubular projections h, substantially as set forth.

2. The draft-pipe K, having its lower part, u, of conical form, with an opening, o, at its lower end, in connection with one or more draft-tubes, H, and a chamber, J, or its equivalent, arranged in relation with the hot-air chamber D, with or without deflector G, and smoke-pipe L, to form a self-cleaning device, as set forth.

JEHIAL H. SIMONDS
